UNITED STATES PATENT OFFICE.

FREDERICK SCHLUETER, OF NEW YORK, N. Y.

GAME-TABLE.

SPECIFICATION forming part of Letters Patent No. 290,360, dated December 18, 1883.

Application filed September 5, 1883. (No model.)

To all whom it may concern:

Be it known that I, FREDERICK SCHLUETER, a citizen of the United States, residing at New York, in the State of New York, have invented 5 a new and Improved Game-Table, of which the following is a specification.

The nature of my invention consists in the construction of a table similar to a billiard or bagatelle-table, with a fixed cushion in its central 10 part and a number of pockets or holes in the face of the table, whereby by the use of a number of balls and a billiard-cue a new game is produced.

The accompanying drawing represents a top 15 view of my improved game-table.

A represents the top of the table, made of any desirable size, and provided with cushions C similar to a billiard-table. I prefer to make the same about three feet wide by seven feet 20 four inches long.

In the center of the table, near the upper end, a cushion, B, is firmly attached, constructed similar to the side cushions, C. This cushion B is made circular, but the same may be 25 made flat or straight on its upper side.

The holes or pockets *a a* (of which there are 30 nine, although their number may be increased or diminished) are arranged as shown in the drawing—namely, three above or behind the fixed cushion B and three on each side. The holes pass through the table, and if provided with pockets the same must be of sufficient size to receive two or more balls, or the holes may connect with a suitable channel on the 35 underside of the table through which the balls are carried to the front of the table.

The game is played with nine (more or less)

balls, one of which must be colored. The colored ball is spotted at *m*, between the three upper holes *a*, and if pushed into any one of 40 holes counts double the value marked on each hole. I have marked these holes 3, 4, 5, 6, 7, 8, 18, 19, and 30; but any other valuation may be given. The white or plain balls are placed upon a line and between the spots *n n'* or *n n''*, 45 and are driven by means of a billiard-cue, so that they first strike against the fixed cushion B and then into any one of the holes *a*. Any ball not going into a hole and not below the holes *a³* and *a⁴*, may be pushed by contact with 50 another ball into any of the holes; but if any ball passes below the holes *a³* *a⁴*, the same must be removed. Any white ball going into a hole, after first having come in contact with the fixed cushions B, counts whatever value is 55 marked upon that hole.

I do not claim a central cushion on a billiard-table, nor a number of holes in the upper end of a table similar, as in a bagatelle-table, by themselves and independent of each 60 other; but

What I claim as my invention, and desire to secure by Letters Patent, is—

A table, A, provided with side cushions, C, in combination with a fixed circular central 65 cushion, B, and a series of holes, *a a*, arranged around the sides and upper end of said cushion B, in the manner and for the purpose substantially as set forth.

FREDERICK SCHLUETER.
